UNITED STATES PATENT OFFICE.

JOHN H. MUELLER, OF OAKLEY, ILLINOIS.

BACK-SUPPORTER.

No. 880,904.

Specification of Letters Patent.

Patented March 3, 1908.

Application filed September 19, 1907. Serial No. 393,746.

To all whom it may concern:

Be it known that I, JOHN H. MUELLER, a citizen of the United States, residing at Oakley, in the county of Macon, State of Illinois, 5 have invented certain new and useful Improvements in Back-Supporters; and I do hereby declare the following to be a full, clear, and exact description of the invention, such as will enable others skilled in the art to 10 which it appertains to make and use the same.

This invention relates to back supporters or braces and is designed for use by persons employed as cotton pickers, corn shuckers, 15 and other occupations requiring considerable bending of the back.

I further have in view the provision of a support of this class which will be adaptable to persons of different build without requiring 20 adjustments and which may be readily applied and removed and when applied, will effectually brace the user's back.

In the accompanying drawings, Figure 1 is a view showing the supporter applied, and, 25 Fig. 2 is a detail view of the supporter when removed.

As shown in the drawings the supporter is of composite construction being made up of padded inelastic sections and elastic sections 30 which are interposed between the said padded inelastic sections. As stated above, the supporter is made up of inelastic and elastic sections and of the former there are four, two of them being in the form of leg bands and the 35 other two in the form of shoulder straps or pads, while of the latter sections there are three, two being interposed between the leg bands and the corresponding shoulder straps and the third one between the two shoulder 40 straps themselves, the leg bands being of course located one at each end of the supporter. Each of the leg bands is indicated by the numeral 5 and is formed of a length of cloth which is folded lengthwise and stitched 45 substantially in a line with the middle of the cloth or strip. These bands are unpadded except for a short distance of their extent and these padded portions, indicated by the numeral 6, are formed by cutting the length 50 of cloth of greater width for the proper dis-

tance and then stuffing and stitching the edges together, as indicated at 7.

As heretofore stated certain of the elastic sections are connected with the leg bands and these sections are indicated by the numeral 8 and may be formed of garter elastic or any other suitable elastic material. As a means for connecting these elastic sections 8 with the leg bands, a loop 9 of cloth is stitched at its ends to each of the bands 5 60 adjacent the padded portions 6 and the elastic of the corresponding sections 8 is passed through these loops and has its ends inserted in one of the ends of the corresponding shoulder pieces which are indicated by the 65 numeral 10 and stitched thereto, these shoulder pieces being formed in identically the same manner as the leg bands except their ends are not stitched one to the other as in the case of the leg bands. These shoulder 70 pieces are provided with padded portions 11 which are so located that when the device is applied to the body they will rest directly on top of the shoulders. The ends of the two shoulder pieces other than their ends to 75 which the elastic sections 8 are connected, are connected by means of an elastic section 12 which is, as in the case of the sections 8, preferably formed of garter elastic although other suitable elastic material may be used. 80

The construction of the entire supporter having now been made clear, a statement of its manner of application to the body will now be given: In applying the supporter to the body the user inserts his legs through the 85 leg bands and then turns the supporter so that the elastic sections 8 will intersect each other across his back immediately below the shoulders. The shoulder sections will then extend from his shoulders with their padded 90 portions resting directly upon his shoulders and the elastic section 12 will extend across his back at a point below the shoulders but above the point of intersection of the elastic sections 8. 95

What is claimed, is—

1. A back supporter comprising inelastic leg bands which are padded throughout a portion of their extent, elastic sections connected to the leg bands adjacent the padded 100

portions, inelastic padded shoulder sections connected to the other ends of the said elastic sections, and an elastic section connecting the other ends of the shoulder sections.

- 5 2. A supporter of the class described comprising leg bands, loops attached to the leg bands, elastic sections passed through the loops, inelastic padded shoulder sections to which the ends of the elastic sections are

stitched, and an elastic section connecting 10 the two inelastic shoulder sections, substantially as described.

In testimony whereof, I affix my signature, in presence of two witnesses.

JOHN H. MUELLER.
